PLAYGROUND SLIDE APPARATUS

Claude W. Ahrens, West Highway 6,
Grinnell, Iowa 50112

Filed Sept. 18, 1970, Ser. No. 25,056

Term of patent 14 years

Int. Cl. D21—03

U.S. Cl. D34—5

FIG. 1

FIG. 1 is a perspective view of the playground slide apparatus showing my new design.

FIG. 2 is a perspective view of the playground slide apparatus looking at the sides thereof opposite the sides shown in FIG. 1; and

FIG. 3 is a reduced top view of the apparatus shown in FIGS. 1 and 2.

I claim:

The ornamental design for a playground slide apparatus, substantially as shown.
